US0D1022910S

(12) **United States Design Patent** (10) Patent No.: **US D1,022,910 S**
Greiser et al. (45) Date of Patent: ** Apr. 16, 2024

(54) **BASEPLATE OF A MODULAR EQUIPMENT FOR DISTRIBUTION OF ELECTRIC POWER AND DATA SIGNALS**

(71) Applicant: **Beckhoff Automation GmbH**, Verl (DE)

(72) Inventors: **Frank Greiser**, Rheda-Wiedenbrück (DE); **Hans Beckhoff**, Verl (DE)

(**) Term: **15 Years**

(21) Appl. No.: **35/515,108**

(22) Filed: **May 18, 2022**

(80) **Hague Agreement Data**

Int. Filing Date: **May 18, 2022**

Int. Reg. No.: **DM/223145**

Int. Reg. Date: **May 18, 2022**

Int. Reg. Pub. Date: **Sep. 9, 2022**

(30) **Foreign Application Priority Data**

Nov. 19, 2021 (EM) 008768477-0006

(51) **LOC (14) Cl.** **13-02**

(52) **U.S. Cl.**

USPC **D13/123**
